2,247,778

ELECTRIC SOCKET

Merrill C. Hoxie, Eggertsville, N. Y., assignor to
 General Electric Company, a corporation of
 New York

Application July 4, 1939, Serial No. 282,781

15 Claims. (Cl. 173—347)

The present invention relates to electrical connectors, and more particularly to a combined socket and switch. The socket of the present invention is well adapted for mounting and controlling a lamp having a plurality of filaments.

It is an object of this invention to provide a new and improved snap switch mechanism.

It is another object of this invention to provide an improved rotary snap switch mechanism having more than two circuit-controlling positions to which it may be operated by rotation in either direction.

It is a further object of this invention to provide a combined socket and switch construction requiring few parts, which are easily assembled and which may be manufactured at low cost.

Further objects and advantages will become apparent as the following description proceeds, reference being had to the accompanying drawing in which Fig. 1 is an elevational view, in section, of a socket embodying the present invention; Fig. 2 is an elevational view partially broken away; Fig. 3 is a top view of the socket of Fig. 1; Fig. 4 is a sectional view taken along the line 4—4 of Fig. 1; Fig. 5 is an exploded view showing the parts of the switch mechanism, and Figs. 6 to 9 show the switch mechanism in its different circuit-controlling positions.

Referring to the drawing, a socket body 10 of generally cylindrical shape is formed of suitable insulating material such as a molded phenolic condensation product. The body is provided with axially extending recesses 11 and 12 which open at opposite ends of the body and are adapted to receive the socket parts and switch mechanism respectively. In the construction shown, a transverse barrier 13 molded integrally with the socket body separates the recesses 11 and 12 and provides a support for parts of the socket and switching mechanism.

The current conducting parts of the socket include a shell contact 14, a central contact 15 and an intermediate contact 16. The shell contact, which may be of the screw thread type, is provided at its lower edge with integral inturned flanges 17 and 18. The central and intermediate contacts 15 and 16 are formed on one arm of the L-shaped stampings 19 and 20 respectively. The stampings 19 and 20 are assembled in the body with the arms including the contacts 15 and 16 extending substantially parallel to the barrier 13 and with the other arms extending axially of the socket body through spaced openings 21 and 22 in the barrier 13 and into the recess 12. It is essential that the central and intermediate

contacts 15 and 16 be insulated from each other and from the shell contact 14 and to this end the flange 18 is provided with spaced notches 23 and 24 in alignment with the openings 21 and 22 and wider than the arms of the L-shaped stampings 19 and 20. A spherical depression 25 formed in each of the L-shaped members 19 and 20 engages a similarly shaped depression (not shown) on the face of the barrier 13 and cooperates with the walls of openings 21 and 22 to position the stampings and prevent them from moving into engagement with the flange 18 of the contact shell. A helical spring 26 is interposed between the central contact 15 and the barrier 13 to increase the resilience of the contact and insure a good electrical connection with the central contact of a lamp received in the socket. A washer 27 of insulating material and an overlying metal plate 28 are clamped against the flange 18 of the contact shell 14 and the L-shaped members 19 and 20 to secure them in the recess 12. A metal plate or washer 29 is clamped against the flange 17 of the contact shell 14.

A pair of conducting terminal straps 30 and 31 having integral lugs 32 and 33 respectively extending from one end thereof are positioned in the recess 12 in spaced parallel relation. The lug 32 passes through aligned openings in the barrier 13, the flange 17 of the shell contact and the washer 29. The lug is peened over or otherwise deformed into engagement with the upper surface of the conducting plate 29 to clamp the plate against the flange 17 and connect electrically the strap 30 to the shell contact 14. In a similar way the lugs 33 of the terminal strap 31 extend through the barrier 13, the insulating washer 27, and the plate 28 against the outer surface of which they are deformed. As will be apparent as the description proceeds, it is essential that the strap 31 be insulated from the socket contacts and for this reason the central portion of the flange 18 is cut away as illustrated by the dotted lines of Fig. 3, so that the lugs 33 do not pass therethrough. Shoulders 34 on each of the straps adjacent the lugs engage the lower face of the barrier 13 and prevent the straps from moving endwise relative to the socket body. The lower end of each strap is provided with an outwardly extending terminal portion 35, the ends of which are received in the axially extending grooves 36 and 37 formed in the side walls of the recess 12. A disk of insulating material 38 provided with spaced apertures for the reception of the terminal straps is assembled thereon before the terminal straps are secured to the barrier 13.

The disk is held from endwise movement by engagement with the upper faces of the terminals 35 and lower ends of the axially extending ribs 39 and provides additional lateral support for the terminal straps 30 and 31.

The terminal straps 30 and 31 serve as supports for the switching mechanism and, in addition, the strap 31 forms a fixed contact for the switch. The movable switch contacts 40 and 41 are formed integral with the resilient axially extending arms of the L-shaped stampings 19 and 20 and are biased thereby toward engagement with the laterally extending ears 42 and 43 of the strap 31.

For controlling the electric circuit between the movable contacts 40 and 41 and the ears 42 and 43 of the terminal strap 31, an insulating disk 44 is provided. The disk is mounted on the strap 31 for rotation relative thereto by a hub 45 which is positioned in an opening 46 formed in the terminal strap between the ears 42 and 43. The hub which may be stamped from suitable sheet metal is secured to one face of the disk by integral tabs 47 which extend through openings 48 and are bent over against the opposite face of the disk. The disk lies between the movable contacts 40 and 41 and the strap 31 and serves to separate them when the disk is rotated from a closed circuit to an open circuit position. The disk is provided with suitable segmental notches 49 and 50 and a segmental opening 51 which permit the movable contacts 40 and 41 to engage the ears 42 and 43 to control the flow of current therebetween in a manner to be more fully set forth in connection with the operation of the switch.

In order to rotate the circuit-controlling disk 44 from one position to another with a snap action, an actuating spring 52 is provided. This spring is in the form of an open loop of wire having a pair of resilient arms 53 normally lying in the same plane and each of which has a straight portion 54 near the end thereof. The straight portions of the spring extend in generally parallel relation and are positioned in elongated openings 55 formed in the insulating disk 44 at diametrically opposite points adjacent the outer surface of the hub 45. A plurality of angularly displaced positioning slots 56 are formed in the terminal strap 31. These slots extend radially from the opening 46 and in a four-position switch as illustrated are spaced 90 degrees apart. The straight portions 54 of the spring arms are positioned in the elongated openings 55 of the circuit controlling disk and certain of the positioning slots 56 which are in alignment therewith when the disk is in one of its circuit controlling positions. The ends 57 of the spring arms are bent outwardly to hold them from slipping endwise out of the elongated openings 55. The closed end of the spring is provided with an offset portion 58 which is received in an opening in the terminal strap 30 in alignment with the opening 46 of the terminal strap 31. A grommet 59 of rubber or similar insulating material is positioned in the opening and serves to insulate the spring 52 from the terminal strap 30. An operating member is provided by a key 60 of insulating material which extends through a suitable opening in the wall of the socket body in alignment with the opening in the grommet 59. The key is provided with a slotted end 61 which is rotatably mounted in the grommet and receives the offset portion 58 of the actuating spring 52 to form a driving connection therewith. The key 60 is held in the

socket body by a bowed spring retainer 62 which lies adjacent one wall of the body in the axially extending recess 36. An insulating plate 63 lying in the recess 36 between the retainer spring 62 and the wall of the socket body is provided with shoulders 64 which engage the insulating disk 38 to hold it against the terminal portions 35 of the conducting strap. The plate 63 is also provided with an opening 65 in which the key 60 is positioned.

The resilience of the spring arms 53 normally biases them outwardly and retains them in the positioning slots 56 of the terminal strap 31. When the key 60 is rotated the spring 52 is distorted due to torsional stress and the end portions thereof are drawn radially inwardly until they are released from the positioning slots 56 at which time they are received in the axially extending grooves 66 formed on the hub 45 in alignment with the elongated openings 55 of the circuit-controlling disk. The energy stored in the spring by virtue of its torsional distortion is effective to rotate the disk with a snap action. When the ends of the spring reach the next set of notches 56, they are moved outwardly by the resilience of the spring and lock the disk relative to the conducting strap 31. With this construction it is apparent that the disk may be rotated in either direction with a snap action by simply rotating the operating key in the desired direction. This feature is particularly advantageous in sockets for multi-filament lamps inasmuch as it permits the switch to be turned back to the last preceding operating position without moving the switching mechanism through a complete cycle of operation.

An insulating washer 67 and a metal cover plate 68 are provided to close the lower end of the socket body and are secured thereto by screws 69 which pass through the barrier 13 and threadingly engage the openings 70 formed in the cover plate. The cover plate and washer are positioned on the socket body by integral lugs 71 which engage suitable notches (not shown) in the lower end of the socket body. The cover plate is provided with an internally threaded nipple 72 which is located centrally of the plate and serves as a support for the socket as well as a passage for the circuit wires (not shown) which are to be connected to the terminals 35 by suitable binding screws 73.

In Figs. 6 to 9 the terminal strap 31, the insulating disk 44 and the movable switch contacts 40 and 41 are shown in the four operative positions which they may occupy in the particular construction illustrated. In Fig. 6 the parts are shown in the position they occupy in the switch, as it is illustrated in Figs. 1 and 2. In this position it is apparent that the movable contact 41 is connected to the ear 43 through the notch 50 in the circuit-controlling disk 44. The movable contact 40 is separated from the ear 42 by a portion of the insulating disk. With the parts in the position just described an electric circuit is completed from the terminal strap 30, through the shell terminal 14, one filament of a lamp (not shown), the intermediate contact 16, the movable contact 41, the ear 43, to the conducting strap 31. When the disk 44 is rotated 90 degrees in a clockwise direction, as viewed in Fig. 6, to the position shown in Fig. 7, the movable switch contact 40 connected to the central contact 15 is allowed to engage the ear 42 of the conducting strap 31 through the opening 51. The movable

switch contact 41 which is connected to the intermediate contact 16 engages the ear 43 through the notch 49 of the insulating disk. In this position of the switch it is apparent that both the intermediate and central contacts of the socket are electrically connected to the conducting strap 31. In Fig. 8 the switch has been rotated another quarter turn in a clockwise direction and as apparent from the figure both of the movable switch contacts 40 and 41 have been moved away from the ears 42 and 43 by the disk 44 and are insulated therefrom by a portion of the disk. In Fig. 9 after another quarter turn in a clockwise direction the contact 41 is insulated from the ear 43 of the terminal strap and the contact 40 is connected to the ear 42 through the notch 49 in the insulating disk.

As best illustrated in Figs. 6 to 9, the movable contacts 40 and 41 are arranged at different radial distances from the center of rotation of the disk 44, so that their circuit-controlling position is controlled by different annular portions of the disk. As illustrated, the contact 40 is arranged nearer the center of the disk and is controlled by the deeper notch 49 and the aperture 51, while the contact 41 is controlled by the notches 49 and 50. In the present construction the movable contacts 40 and 41 are biased toward the fixed contact formed by the conducting strap 31 and are controlled by the interposed disk 44. It will be apparent to those skilled in the art that the contacts 40 and 41 may be biased away from the strap 31 and the disk 44 arranged to move them sequentially into engagement there-with as the disk is rotated from one circuit-controlling position to another.

The improved snap-acting mechanism and the simplified arrangement of the socket and switch contacts are considered important features of the present invention.

What I claim as new and desire to secure by Letters Patent of the United States, is:

1. In an electric switch, a support, a plurality of contacts non-rotatably mounted with respect to said support and at least one of which is movable and biased to one circuit controlling position, a rotatable circuit controller for moving said movable contact to another circuit controlling position, and means including a spring in the form of an open loop having spaced resilient arms operatively connected with said circuit controller for rotating said circuit controller with a snap action.

2. A snap acting mechanism for an electric switch comprising a rotatable circuit controller having a plurality of circuit controlling positions, a spring member including a pair of spaced resilient arms lying in substantially the same plane and having a driving connection with said circuit controller, means for restraining the ends of said arms in a plurality of angularly displaced positions corresponding to the circuit controlling positions of said controller, and means for rotating the unrestrained portion of said spring to distort said spring and move said spring arms toward each other and thereby to release said spring arms from said restraining means so that said spring arms and said circuit controller are rotated to another position with a snap action by the energy stored in said spring.

3. A snap acting mechanism for an electric switch, comprising a support having an aperture therein, a plurality of positioning means angularly displaced around said aperture, a spring

5 member having spaced resilient arms extending through said aperture and normally held against rotation by certain of said positioning means, a circuit controller having a driving connection with said spring arms, and means for rotating a portion of said spring between said arms to distort said spring and release said arms from said positioning means so that the energy stored in said spring by the distortion thereof rotates said circuit controller with a snap action.

4. A snap acting mechanism for an electric switch, comprising an insulating housing, a pair of supporting straps extending in spaced relation in said housing and having aligned apertures therein, one of said straps having a plurality of positioning slots communicating with the aperture therein, an open-ended spring member having a pair of resilient arms positioned in certain of said positioning slots, the closed end of said spring having an offset portion received in the aperture of the other of said straps to mount said spring for rotation about an axis passing through said apertures, an operating key rotatably mounted with respect to said casing and having a slotted end extending through the aperture in said last-mentioned strap with the offset portion of said spring received in said slot to form a driving connection therewith.

5. A snap acting mechanism for an electric switch, comprising a support having an aperture and a plurality of spaced positioning slots communicating therewith, a circuit controlling member mounted for rotation relative to said support and having openings formed therein in alignment with certain of said positioning slots, a spring member having resilient arms each of which is positioned at one end in one of said openings and the positioning slot in alignment therewith, and means for rotating a portion of said spring between said arms to distort said spring and release said arms from said positioning slots whereby the energy stored in said spring by the distortion thereof rotates said circuit controlling member with a snap action.

45 6. A snap acting mechanism for an electric switch comprising a support having an aperture and a plurality of spaced positioning slots communicating therewith, a circuit controlling disk of insulating material having a hub positioned 50 in said aperture and mounting said disk for rotation relative to said support, said disk having openings formed therein in alignment with certain of said positioning slots, said hub having axially extending grooves formed therein in alignment with said openings, a spring member having a pair of spaced resilient arms each of which is positioned at one end in one of said 55 openings and the positioning slot in alignment therewith, said arms being normally biased outwardly to hold said arms in said positioning slots, means for rotating a portion of said spring between said arms to distort said spring and move said arms inwardly from said positioning slots and into the grooves formed in said hub whereby the energy stored in said spring by the distortion thereof rotates said circuit controlling member with a snap action.

7. In an electric switch, a conducting strap including a fixed contact having an aperture formed therein with a plurality of spaced positioning slots communicating therewith, a movable contact normally biased to one circuit controlling position, a disk of insulating material 70 rotatably mounted with respect to said conduct-

ing strap for moving said movable contact to another circuit controlling position, said disk having openings formed therein in alignment with certain of said positioning slots, a spring member having resilient arms each of which is positioned near one end in one of said openings and the positioning slot in alignment therewith, and means for rotating a portion of said spring between said arms to distort said spring and move said arms inwardly whereby said arms are released from said positioning slots and the energy stored in said spring rotates said disk with a snap action.

8. In an electric socket, a shell contact, a central contact and an intermediate contact, a fixed switch contact, movable switch contacts electrically connected to said central and intermediate contacts respectively, a circuit controller having more than two angularly displaced circuit controlling positions mounted for rotation relative to said fixed contact and constructed and arranged to control the engagement of said fixed and movable contacts, an operating member and spring means interconnecting said operating member and said circuit controller for rotating said circuit controller in either direction with a snap action.

9. In an electric socket, a support of insulating material, a shell contact positioned on one side of said support, a pair of substantially L-shaped members of conducting material positioned in spaced relation on said support with one arm of each of said members lying along said one side of said support and within said shell contact and with the other arm of each of said members extending through said support and substantially parallel to the axis of said shell contact, means overlying a portion of said shell contact and said L-shaped members to secure said shell contact and said L-shaped members to said support in insulated relation, a contact formed near the end of each arm extending through said support and forming movable switch contacts, a fixed switch contact arranged to cooperate with said movable switch contacts, and means for controlling the engagement of said fixed and movable contacts.

10. An electric socket comprising a support of insulating material, a shell contact, a central contact and an intermediate contact positioned on one side of said support, said central and intermediate contacts each having an arm extending along said one side of said support and each having an arm extending through an opening in said support in a direction substantially parallel to the axis of said shell contact, means for securing said contacts to said support in insulated relation, a fixed switch contact disposed on the side of said support opposite said shell contact, the axially extending arms of said central and intermediate contacts forming movable switch contacts normally biased to engagement with said fixed contact, and a circuit controller of insulating material lying between fixed and movable switch contacts and having a plurality of segmental openings therein for controlling the engagement of said fixed and movable contacts.

11. In an electric socket, a body of insulating material, a shell contact secured in said body, a pair of substantially L-shaped members of conducting material secured in said body in insulated relation, a contact formed on each end of each of said L-shaped members, one contact of each of said members being arranged within said shell contact and the other contacts of said members

forming movable switch contacts, a conducting strap mounted in said body, a circuit controller of insulating material mounted for rotation with respect to said conducting strap for controlling the engagement of said movable contacts with said conducting strap, an operating member, and means including a spring in the form of an open loop interposed between said operating member and said circuit controller for rotating said circuit controller with a snap action in response to rotation of said operating member.

12. In an electric socket, a body of insulating material recessed from its opposite ends and provided with a transverse barrier, a shell contact, a central contact and an intermediate contact positioned in one of said recesses, a conducting strap in the other of said recesses forming a fixed switch contact, said central and intermediate contacts each having a resilient arm extending into said other recess and forming movable switch contacts normally biased toward said conducting strap, a disk of insulating material rotatably mounted on said conducting strap and positioned between said strap and said movable contacts, said disk having a plurality of segmental openings for controlling the engagement of said movable contacts with said conducting strap, and means for rotating said disk with a snap action.

13. In an electric socket, a body of insulating material recessed from its opposite ends and including a transverse barrier, a conducting strap in one of said recesses extending axially of said body and having an integral lug extending through said barrier, a shell contact and a central contact positioned in the other of said recesses, a plate of insulating material overlying a portion of each of said contacts, said lug being deformed at its outer end to clamp said plate of insulating material against said contacts and hold them assembled in said other recess in electrically insulated relation, said central contact having a resilient arm extending through said barrier and forming a movable switch contact adapted to engage said conducting strap, a circuit controller of insulating material rotatably mounted with respect to said conducting strap for controlling the engagement of said movable contact with said strap, and means for rotating said circuit controller.

14. In an electric socket, a body of insulating material recessed from its opposite ends and including a transverse barrier, a pair of conducting straps positioned in one of said recesses in spaced relation and each having an integral lug at one end extending through said barrier and a terminal portion at the other end, a shell contact, a central contact and an intermediate contact positioned in the other of said recesses, the lug of one of said conducting straps being deformed to secure said shell contact in said other recess and to connect electrically said strap and said shell contact, a plate of insulating material engaging said central contact, said intermediate contact and a portion of said shell contact, the lug of said other conducting strap being deformed to clamp said plate of insulating material against said contacts to hold them in said other recess in electrically insulated relation, said central and intermediate contacts each having a resilient arm extending through said barrier and forming movable switch contacts adapted to engage said one conducting strap, a circuit controller of insulating material rotatably mounted with respect to said straps for controlling the engagement of said movable contacts with said other conducting

strap, and means for rotating said circuit controller.

15. A snap acting mechanism for an electric switch comprising a support having an aperture and more than two angularly spaced positioning means around said aperture, a circuit controller mounted for rotation relative to said support and having an opening formed therein in alignment with one of said positioning means in one circuit controlling position of said controller, a spring 10 having an arm extending in a plane substantially

perpendicular to the plane of rotation of said circuit controller, said arm having one end positioned in said opening and engaging the positioning means in alignment therewith, and means for 5 rotating a portion of said spring spaced from said controller to distort said spring and release said arm from said positioning means so that the energy stored in said spring by the distortion thereof rotates said circuit controlling member with a snap action.

MERRILL C. HOXIE.
